BELL PISTON PUMP

John B. McGay, Tulsa, Okla.

Application September 6, 1956, Serial No. 608,374

5 Claims. (Cl. 103—46)

This invention relates to improvements in pumping apparatus, and more particularly, but not by way of limitation, to a novel bottom hole pump designed for utilization in deep well bores for pumping the fluid therein to the surface of the ground.

When the fluid pressures in an oil reservoir are not sufficiently high to raise the fluids in the well bore to the surface of the ground by natural flow, it is necessary to provide an artificial method for lifting the fluid within the bore. Many producing oil wells of today utilize a bottom hole pump for pumping the well fluid upwardly through the well bore for production thereof at the surface of the ground. These pumps are often rod actuated pumps wherein the pumping member is disposed at the bottom of the well bore and is actuated from the surface by means of a string of rods extending downwardly in the well bore. The well bore is usually crooked or diverges from a true vertical disposition as it extends downwardly in the earth. It will be apparent that this condition will be greatly exaggerated in excessively deep well bores. The substantially straight rod members extending through the crooked bore hole often rub against the well casing or well bore upon reciprocation therein and become disjointed, worn out, and, therefore, ineffective for actuation of the pump. Furthermore, as the depth of a well bore increases, it becomes increasingly difficult to raise the fluid therein by rod actuated bottom hole pump to the surface of the well for production. Thus, as the oil industry increases the drilling of deep well bores, the problem of actuating the bottom hole pump from the surface of the well to lift the well fluid is greatly increased.

The present invention contemplates a novel bottom hole pump particularly designed and constructed to facilitate the pumping of fluid from the deep well bore. A bell piston operating in a rather long cylinder is provided at the bottom of the bore. When this cylinder, attached to the end of the well tubing, is lowered into the well the whole of the cylinder and tubing contains air at atmospheric pressure, and when the tubing is primed by filling it with fluid from the top of the well, the air in the cylinder is compressed into the space inside the bell piston, thus creating a high pressure inside the bell piston without the necessity of pre-charging the air chamber with high pressure air. The bell piston is reciprocated in the cylinder by changes in fluid pressure in the tubing, which changes in pressure are created by the reciprocation of a piston member near the surface of the ground.

A quick opening toggle valve is provided at the surface of the well for discharging the well fluid from the tubing. When the piston member at the surface has driven the fluid downward in the tubing, thus compressing the air in the bell piston, this toggle valve snaps open from mechanical connection with the well jack and the compressed air in the bell piston drives the piston and the column of fluid in the tubing upward at high velocity. When the bell piston reaches the end of its travel it stops

2

suddenly, but the column of fluid tends to continue its upward movement, thus creating a vacuum at the head of the bell piston and drawing in well fluid through the standing or bottom hole valve. Thus, the present invention provides a novel bottom hole pumping apparatus which is simple and efficient in operation, and economical and durable in construction.

It is an important object of this invention to provide a novel pumping apparatus for a well bore whereby a bell piston is disposed on the lowermost portion of the well tubing for reciprocation by fluid pressure differentials, thereby eliminating the use of sucker rods, and the like, extending downwardly throughout the length of the well bore.

15 It is another object of this invention to provide a novel bottom hole pumping apparatus for a well bore wherein the pump may be easily and simply charged with atmospheric pressure prior to pumping operation of the apparatus.

20 It is still another object of this invention to provide a bottom hole pumping apparatus for deep well bores wherein the pumping member is actuated by means of an off-set piston having a relatively short stroke to provide pressure on the upstroke thereof so that the novel 25 pump may be utilized with the normal well pumping jack members.

It is a further object of this invention to provide a bottom hole pumping apparatus wherein a quick opening valve is utilized to relieve the head pressure in the tubing 30 at the instant required for the most efficient operation of the pumping unit to provide a snapping action for the bell piston member to lower the pressure at the bottom of the tubing for rapidly sucking the oil from the reservoir into the tubing.

35 Other objects and advantages of the invention will be evident from the following detailed description, read in conjunction with the accompanying drawings, which illustrate my invention.

In the drawings:

40 Figure 1 is a broken sectional elevational view of a bottom hole pump embodying the invention disposed within a well bore, and depicting the pump in one position of operation.

45 Figure 2 is a similar view to Fig. 1 with the pump in another position of operation.

Referring to the drawings in detail, a string of tubing 10 is longitudinally disposed within a well bore 12 in any well known manner such that the lowermost portion of 50 the tubing extends downwardly into communication with the oil reservoir in the well bore 12. A suitable foot valve member or standing valve 14 is provided at the lower end 16 of the tubing 10 for directing fluid into the tubing from the oil reservoir in the annular space 17. A pumping unit, generally indicated at 18, is secured below the foot valve 14 in substantially longitudinal alignment with the tubing 10 by means of a suitable sleeve member 20. The pumping unit 18 comprises a cylindrical housing member 22 having an aperture 24 at the 60 top thereof in communication with the tubing 10 through the sleeve member 20. The bottom of the cylinder 22 is closed at 21 to provide a chamber 23 therein. The aperture 24 provides an annular shoulder 25 at the uppermost end of the cylinder 22. An air bell piston member 26 is slidably disposed within the housing 22. A helical spring member 28 having one end anchored on the end member 21 supports the bell piston 26 and constantly urges the piston upwardly within the cylinder 22. The spring member 28 is so designed to provide only a slight or negligible force on the piston 26 in order that 70 reciprocation of the piston within the cylinder during the operation of the pump 18 will be determined entirely

by the fluid pressure differentials acting thereon as will be hereinafter set forth.

The piston head portion 29 of the bell piston 26 is provided with a plurality of suction cup members 30 for precluding the flow of fluid around the piston head. A resilient annular ring member 32 is disposed at the top of the piston head 29 to provide a bumper or cushioning action for the piston 26 during an upward movement thereof into contact with the shoulder 25. A threaded insert member 34 having a longitudinal bore or passageway 36 extending therethrough is threadedly secured within the piston head 29. A circumferential flange member 37 is provided on the threaded insert member 34 for retaining the ring member 32 securely in position on the piston head 29. The piston head is provided with a threaded bore 38 for receiving the insert member 34. The threaded bore 38 is of a greater length than the insert member 34, as clearly shown in the drawings, such that a chamber 39 is provided in communication with the longitudinal bore 36 of the insert member 34. A radial passageway 40 extends outwardly from the chamber 39 to provide communication between the chamber 39 and the annular space 42 between the piston 26 and the cylinder 22 for a purpose as will be hereinafter set forth.

The well bore 12 is enlarged at 44 near the surface of the earth to receive a cylinder 46 adjacent the well tubing string 10. The cylinder 46 is open at the lower end 48 thereof and the upper end is in communication with the well tubing at a port 49. A piston member 50 is reciprocally disposed with the open cylinder 46, and is vertically reciprocated therein by means of a polished rod 52 extending upwardly therefrom through a suitable stuffing box member 54. The polished rod 52 is actuated or vertically reciprocated in any well known manner by means of a suitable well jack apparatus 56 and suitable actuator 57. It will be apparent that fluid pressure fluctuations within the open cylinder 46 created by reciprocation of the piston 50 therein will be communicated through the port 49 to the interior of tubing 10 and downwardly therethrough to the pumping unit 18.

A port 58 (Fig. 2) is provided in communication with the well tubing 10 to provide a seat for a suitable quick opening toggle valve member 60. Well fluid from the well tubing 10 is discharged through the port 58 for storage, or the like, as determined by the open or closed position of the toggle valve 60, as will be hereinafter set forth. The valve 60 is connected to the well jack 56 by means of a suitable bell crank or toggle mechanism 62 which is pivotally secured to a connecting rod member 63. A pair of spaced stop members 64 and 65 are provided on the connecting rod 63 for cooperation with a recessed flange member 67 provided on the pump jack 56 for contact thereby to alternately open and close the valve 60. It will be apparent that the valve 60 is open during the downstroke of the jack 56, as shown in Fig. 2, and similarly the valve is closed during the upstroke thereof, as shown in Fig. 1. The operation of the lever arm members 62 by the rod 63 provides for a quick release of the valve 60 upon opening thereof, and securely closes the valve 60 adjacent the seat 58 as the well jack 56 is operated.

Operation

The tubing string 10 is inserted in the well bore 12 in the usual manner (not shown) with the pumping unit 18 secured to the lower end thereof. The pumping unit 18 and the tubing 10 are filled with normal atmospheric air upon being disposed within the well bore, and the normal action of the helical spring 28 will urge the bell piston 26 upwardly in the cylinder 22 into contact with the shoulder 25, as shown in Fig. 2. Priming fluid (indicated at 66 in Fig. 1) is introduced into the tubing 10 through the port 58 and open valve 60 in any suitable well known manner. The priming fluid flows downwardly by gravity through the tubing 10 and the sleeve

5 into contact with the piston head member 29. The fluid is sealed from a downwardly flow around the piston head by the suction cups 30, and will, therefore, pass through the orifice 38 into the small chamber 39 where it is directed through the radial passageway 40 into the annular space 42. The priming fluid collects within the chamber 23 of the cylinder 22 and rises upwardly therein to seal off the lower end of the piston 26, as shown in Fig. 1. The accumulating fluid 66 raises within the bell piston and compresses the air present under the piston head 29. During this priming operation, the static head of the fluid in the tubing 10 may overcome the action of the spring 28 and move the bell piston 26 downwardly slightly within the cylinder 22. If this occurs, however, the spring will slowly move the piston upwardly to a position adjacent the shoulder 25 when the pressure in the chamber 23 becomes equal to the pressure at the lower end 16 of the tubing 10. The air under the piston head 29 is then in a compressed condition and the pressure thereof is equal to the static head of the fluid in the tubing 10. The pump 18 is now ready for the producing operation. As an additional downward force is applied to the top of the fluid within the tubing 10, the fluid column (not shown) is forced downwardly therein to 10 move the bell piston 26 downwardly and further compress the air under the piston head. When the additional force acting on the top of the fluid column is removed or released, the compressed air under the bell piston 26 expands and causes the piston to move rapidly upward 15 until the bumper member 32 seats against the shoulder 25. The upward movement of the piston 26 imparts an upward velocity to the fluid column thereabove within the tubing 10. The piston 26 is suddenly stopped in its upward movement when it strikes the shoulder 25, but 20 the fluid column continues to move upwardly in the tubing 10 due to the initial velocity and mass of the column, thereby creating a vacuum at the lower end 16 of the tubing 10. This lowered pressure, or vacuum, created in the proximity of the foot valve 14 is substantially less than the fluid pressure present in the annulus 25 20. Thus, the valve 14 is opened by the pressure differential acting thereon, as shown in Fig. 2, to permit the well fluid present in the well bore 12 to enter the end 16 of the tubing 10 and replace the fluid being displaced and discharged from the tubing 10.

It will be apparent that a continuous repetition of the alternate application and removal of force on the top of the fluid column in the well tubing 10 will lift the well fluid upwardly through the foot valve 14 and through the tubing 10 for discharge at the surface thereof through the valve 60. The off-set piston 50 is provided in order to create this fluctuating pressure within the tubing. The piston member 50 is normally at the bottom of its stroke, as shown in Fig. 2, at the start of the pumping operation. As the piston 50 is moved upward within the open cylinder 46 by operation of the well jack 56, the fluid pressure above the piston 50 is forced through the port 49 into the tubing 10. The toggle valve 60 remains closed as the piston 50 is moving upward on the power stroke thereof. Therefore, the fluid pressure must move downwardly within the tubing to provide the additional force on the top of the fluid disposed within the tubing 10 for actuation of the pumping unit 18 as hereinbefore set forth. At the upper limit of the power stroke of the piston 50, the well jack contacts the stop member 64 to trip the lever arm mechanism 62 for releasing of the toggle valve 60. The fluid pressure present at the top of the tubing 10 adjacent the valve 60 quickly snaps the released valve 60 to a full open position for discharge of the well fluid from the tubing through the conduit 68 for storage in a stock tank 70, or the like. The release of fluid pressure from the tubing 10 through the valve 60 naturally decreases the downward force on the bell piston 26, thereby permitting the compressed air under the bell piston to rapidly expand. The simultaneous ex-

Expansion of the compressed air and the release of the fluid pressure from the tubing provides an increased momentum for the upward movement of the bell piston to impart an increased velocity for the upward movement of the fluid column thereabove. Thus, the fluid column will continue its upward movement after the bell piston has been suddenly stopped by contact with the shoulder 25, as hereinbefore set forth, to create the vacuum at the lower end 16 of the tubing 10.

The piston 50 draws off a portion of the well fluid from the tubing 10 into the cylinder 46 upon a down stroke of the piston 50, thereby charging the cylinder 46 for the next upstroke, or power stroke, of the piston 50. The reciprocation of the piston 50 is properly timed so that the piston 50 approaches the lower limit of its down stroke at substantially the same time that the flow of fluid in the tubing 10 has ceased. When the flow of fluid through the open valve 60 has stopped, the weight of the valve will drop the valve toward the seat 58. Simultaneously the pump jack 56 will contact the second stop member 65 to actuate the linkage mechanism 62 for closing of the valve securely adjacent the valve seat 58. Thus, the reciprocation of the piston 50 by the well jack 56 intermittently provides additional pressure within the tubing 10 for actuation of the pumping unit 18 to lift the well fluid from the bore 12 to the surface of the earth. The strokes of the pump jack 56 are properly timed to reciprocate the piston 50 for the most efficient operation of the pumping unit 18 as hereinbefore set forth.

From the foregoing, it will be apparent that the present invention provides a novel bottom hole pump for well bores wherein a bell piston is disposed at the lower end of the well tubing. The bell piston and tubing are charged with normal atmospheric air prior to installation thereof within the well bore, thereby eliminating pre-charging of the pump with compressed air, or the like. Fluid pressure differentials acting on the fluid column in the tubing reciprocates the bell piston. An upward movement of the bell piston imparts an upward velocity to the fluid column thereabove for lifting thereof toward the surface of the earth. The sudden stopping of the upward movement of the bell piston creates a vacuum at the lower end of the well tubing whereby the well fluid in the bore is sucked into the tubing to enter the fluid column and is lifted to the surface therewith. The reciprocation of the off-set piston member provides the pressure differentials within the tubing for actuation of the bottom hole bell piston. The timing of the off-set piston is adjusted for opening of the surface toggle valve at exactly the proper moment for discharging the well fluid from the tubing for release of the fluid pressure on the bell piston, and similarly, to close the valve at the instant the flow from the well ceases. The continuous reciprocation or repetition of the cycle of the off-set piston provides for an efficient and economical production of the well fluid from the well bore.

Changes may be made in the combination and arrangement of parts as heretofore set forth in the specification and shown in the drawings, it being understood that any modification in the precise embodiment of the invention may be made within the scope of the following claims without departing from the spirit of the invention.

I claim:

1. A well pumping apparatus comprising a tubing string extending downwardly in a well bore, a fluid column in the tubing, a fluid pressure responsive means disposed at the lower end of the tubing comprising a cylinder member in communication with the tubing, a bell piston reciprocally disposed within the cylinder, a chamber provided under the piston, means providing communication between the tubing and the chamber to direct fluid from the fluid column to the chamber for compressing the air therein, means for applying force to the top of the fluid column for moving the bell piston downwardly and fur-

ther compressing the air thereunder, means for relieving the fluid pressure in the tubing whereby the compressed air expands to move the bell piston upwardly, to provide an upward velocity to the fluid column in the tubing 5 above the piston, valve means responsive to the velocity of the fluid column to provide for discharge of well fluid therefrom.

2. A well pumping apparatus comprising a tubing string extending downwardly in a well bore, a fluid column in 10 the tubing, a fluid pressure responsive means disposed at the lower end of the tubing comprising a cylinder member in communication with the tubing, a bell piston reciprocally disposed within the cylinder, a chamber provided under the piston, means providing communication 15 between the tubing and the chamber to direct fluid from the fluid column to the chamber for compressing the air therein, means for applying force to the top of the fluid column for moving the bell piston downwardly and further compressing the air thereunder, means for relieving 20 the fluid pressure in the tubing whereby the compressed air expands to move the bell piston upwardly, said upward movement imparting an upward velocity to the fluid column in the tubing above the piston for discharge therefrom, means responsive to a vacuum created by upward movement of the column to draw well liquid into 25 the tubing for replacement of the fluid column.

3. A well pumping apparatus in combination with a tubing string extending downwardly in a well bore into communication with an oil reservoir therein, a fluid column in the tubing, a pressure responsive valve member provided at the lower end of the tubing, a fluid pressure responsive means disposed below the valve for moving the fluid column upwardly in the tubing for discharge therefrom, said means comprising a cylinder in communication with the tubing, a bell piston member reciprocally disposed in the cylinder, a chamber beneath the piston, a passageway providing communication between the tubing and the chamber for directing fluid to the chamber to compress the air therein, means for applying force to 30 the top of the fluid column above the piston for moving the bell piston downwardly and further compressing the air thereunder, means for relieving the pressure of the fluid column in the tubing above the piston whereby the compressed air may expand to move the bell piston upwardly, said upward movement imparting an upward velocity to the fluid column for discharge from the tubing, a shoulder provided on the cylinder for limiting the upward movement of the bell piston thereby creating a 35 vacuum in the proximity of the valve member, said vacuum permitting an opening of the valve for discharge of oil from the reservoir into the tubing.

4. A well pump apparatus in combination with a tubing string extending downwardly in a well bore into communication with an oil reservoir therein, a pressure actuated valve member inserted in the tubing string in the proximity of the oil reservoir, a cylinder disposed below the valve in communication with the tubing, a bell piston reciprocally disposed in the cylinder, a piston head provided on the bell piston, means for precluding flow of 40 fluid between the piston head and the cylinder, a chamber beneath the piston head, a passageway for directing fluid into the chamber to compress the air in the chamber, an off-set cylinder member provided adjacent the tubing at the surface of the well bore and in communication with the tubing, a second piston member reciprocally disposed in the off-set cylinder, means for reciprocating the second mentioned piston member, said second piston communicating a downward force in the tubing on the upstroke thereof for moving the bell piston downwardly to further 45 compress the air in the chamber, a quick opening valve member disposed at the surface of the well bore in communication with the well tubing, said quick opening valve adapted to open for discharge of fluid from the tubing to relieve the pressure of the fluid column in the tubing as 50 the second piston member reaches its upper limit of move-

ment, said bell piston moved upwardly by the expanding of the compressed air upon relief of the pressure in the tubing, said upward movement of the bell piston imparting an upward velocity to the fluid column, and means for limiting the upward movement of the bell piston to provide a vacuum adjacent the pressure actuated valve for opening thereof to discharge oil from the reservoir into the tubing.

5. A well pumping apparatus in combination with a tubing string extending downwardly in a well bore having an oil reservoir therein, a fluid column in the tubing, a bell piston member reciprocally disposed at the lower end of the tubing, a piston head provided on the bell piston, a chamber beneath the piston head, a passageway for directing fluid downwardly from the tubing into the chamber whereby the air in the chamber is compressed such that the air pressure therein becomes equal to the static head of the fluid column, a standing valve member interposed in the tubing string above the bell piston, means for exerting a downward force on the top of the fluid

10 column for moving the bell piston downwardly to increase the compression of the air in the chamber, means for relieving the pressure of the fluid column in the tubing for permitting the compressed air to expand thereby moving the bell piston upwardly, said upward movement of the piston imparting an upward velocity of the fluid column for discharging thereof from the tubing, and means for limiting the upward movement of the bell piston to provide a vacuum adjacent the standing valve for discharge of oil from the reservoir into the tubing for replacing the discharged fluid.
